UNITED STATES PATENT OFFICE.

HENRY A. ARMSTRONG, OF BROOKLYN, NEW YORK, ASSIGNOR TO INTERNATIONAL TYPESETTING MACHINE COMPANY, OF NEW YORK, N. Y., A CORPORATION OF NEW YORK.

ELEVATOR-LIFT FOR MACHINES OF THE LINOTYPE CLASS.

1,156,027.

Specification of Letters Patent.

Patented Oct. 5, 1915.

Application filed January 26, 1914. Serial No. 314,515.

To all whom it may concern:

Be it known that I, HENRY A. ARMSTRONG, a citizen of the United States, residing at Brooklyn, in the county of Kings and State 5 of New York, have invented new and useful Improvements in Elevator-Lifts for Machines of the Linotype Class, of which the following is a specification.

My present invention relates to improvements in machines of the linotype class 10 wherein matrices and spacers are assembled into a line by manipulation of the keyboard, the assembled line being then raised by an assembling elevator to a line delivery 15 carriage which latter transfers the line from the assembling elevator to the casting mechanism.

The primary object of the invention is to provide improved means for operating the 20 assembling elevator by power instead of by the manual means usually employed, such power means being released by a key within convenient reach of the operator, and after it has commenced its operation, the elevator 25 is controlled automatically in its rising and falling movements.

To these and other ends, the invention consists in certain improvements, and combinations and arrangements of parts, all as 30 will be hereinafter more fully described, the novel features being pointed out particularly in the claims at the end of the specification.

In the accompanying drawings:—

Figure 1 is a front elevation of a portion 35 of a machine of the class stated and embodying the present invention; Fig. 2 represents an elevation of the structure shown in Fig. 1 as viewed from the right-hand side 40 thereof; Fig. 3 is a detail view of the releasing or controlling finger key; Fig. 4 is a detail view of the mechanism provided by the present invention for operating the assembling elevator, the latter being shown in 45 its elevated or upper position; Fig. 5 is a view of the parts shown in Fig. 4, the elevator being shown in its lower position.

Similar parts are designated by the same reference characters in the several views.

The present invention is applicable generally to typographical machines of the class employing an assembling elevator for raising a line of matrices and spacers to a line transfer carriage.

The preferred embodiment of the invention is shown in the accompanying drawings and the same is illustrated as applied to a machine of the well known linotype class as disclosed fully in the Mergenthaler Patent, No. 436,532, dated September 16, 1890. It is to be understood, however, that the invention is not restricted to the particular construction shown, as equivalent constructions within the scope of the claims at the end of this specification may be used.

In the accompanying drawings, 1 designates an assembling elevator which is movable vertically and may be provided, as usual, with a channel to receive a line of matrices and spacers.

2 designates a star-wheel which rotates continuously and operates to feed or stack the matrices in the channel of the elevator, the matrices being delivered in the usual way from the magazine onto the upper stretch of a continuously moving belt 3 and discharged from this belt onto the star-wheel. Delivery of the desired matrices from the magazine is effected for example in the usual way by manipulation of the keyboard 4.

5 designates the line delivery carriage which, as shown, reciprocates horizontally and operates to transfer a line of matrices and spacers from the assembling elevator 85 when the latter is in its raised or upper position to the casting mechanism, this carriage having a pair of depending fingers 6 and 7 between which the line of matrices and spacers is received. The line delivery carriage is actuated by an arm 8 which is operatively connected at its upper end to the carriage and is mounted at its lower end upon a shaft 9, it being understood that the carriage is released automatically when the elevator reaches its upper position and is carried by spring pressure to the left, thereby sweeping the line of matrices from the elevator into the delivery channel 10, the latter being provided with suitable guides 90 for the lugs of the matrices. Manual means for raising the elevator is shown, it embodying a rock shaft 11 arranged at the front of the keyboard and provided at its right-hand end with a forwardly extending handle 12 and at its left-hand end with a rearwardly extending arm 13, the latter being operatively connected to the elevator by a

link 14 whereby downward pressure on the handle 12 will raise the arm 13 and the link 14, thereby lifting the elevator to its upper position with the line of matrices in position to be received and transferred by the line delivery carriage. The parts described are of the usual construction as used in machines of this class.

The present invention provides power means for raising and lowering the elevator, the movements of the elevator being controlled automatically after the operation thereof has commenced. In the construction shown, a shaft 15 is mounted below and toward the rear of the keyboard, it being shown supported on a stationary bracket 16. A lever 17 is fixed to one end of said shaft and is operatively connected to the elevator by a link 18 which extends downwardly from the elevator and is provided at its lower end with a vertical slot 19 in which a pin 20 on the lever 17 operates. This slot is provided in order that the elevator may be raised manually if desired without disturbing the power means. The lever 17 is provided with a controlling dog 21. A member 22 is also fixed to the shaft 15, it having a track formed thereon and a weight 23 is slideable on said track in a direction transversely of the shaft 15. The weight 23 is operatively connected to the actuating arm 8 for the line delivery carriage, a link 24 being pivotally connected to these parts in the present instance.

The power means for operating the elevator is preferably key-controlled. For this purpose a key lever 25 is provided which is pivoted at 26 and has a finger key 27 at its forward end. A latch 28 is pivoted at 29 on the key lever 25 and is provided with a foot 30 arranged and shaped to cooperate with a foot 31 on the key lever 25. The feet 30 and 31 are normally held in engagement by a tension spring 32 which connects the latch 28 and the key lever 25, and when the latter occupies its normal or raised position the lower end of the latch 28 will engage the upper side of and form a stop for the dog 21, thereby preventing upward movement of the lever 17. Depression or actuation of the key lever 25 will move the latch 28 clear of the dog 21, as shown by the full lines in Fig. 3, and the lever 17 will then be free to rise and thereby carry the elevator to its upper position under the action of the weight 23 which, when the elevator is lowered and the line delivery carriage is in position to receive a line of matrices, will occupy a position on the member 22 to the right of the shaft 15, the weight being so positioned by the link 24. When the power means has been released, the lever 17 acting through the link 18 will lift the elevator until it reaches its upper position, the parts then assuming the position shown

in Fig. 4. When the elevator reaches its upper position, the line delivery carriage is released in the well known or any other suitable way and the arm 8 then moves toward the left, sweeping the line of matrices from the elevator. As the arm 8 moves to the left, the link 24 connected thereto draws the weight 23 toward the left on the member 22 until the weight reaches a position with its center of gravity in vertical alignment with 75 or slightly to the left of the shaft 15, as shown in Fig. 5. When the weight is in this position it no longer acts to raise the elevator and the latter will then descend by its own weight until it reaches its lower position in readiness to receive a new line of matrices. When the line delivery carriage returns to its normal right-hand position, the link 24 acts to shift the weight 23 to the right, thus returning it to the position shown in Fig. 1 where it exerts sufficient force upon the lever 17 to raise the elevator and the line of matrices carried thereby. Should the finger key 27 be depressed before the line delivery carriage has returned to its right-hand position, the elevator would not rise as the weight 23 then would not occupy a position where it would raise the elevator.

The present invention also provides means for preventing action of the weight to raise the elevator should the latter contain an excess number of matrices. To this end the key lever 25 is provided with an extension 33 which is pivotally connected to a link 34, and this link is pivotally connected to one arm of a lever 35 which latter is pivoted to a part of the main frame of the machine at 36, the other arm of the lever 35 having a pin and slot connection 37 with one arm of a lever 38, the latter being pivoted at 39 to a part of the main frame of the machine and its upper end carries a finger 40 which is adapted to pass over the star-wheel 2 and into the entrance of the matrix channel in the elevator. The parts described are so proportioned that when the key lever 25 is actuated to release the power means and cause raising of the elevator, the finger 40 will enter the elevator and should the line contain an excess number of matrices or project from the right-hand or entrance end of the elevator, movement of the latch 28 by the key lever would be arrested before release of the elevator raising lever 17, thus notifying the operator of the fault and permitting the same to be corrected. However, where the line is of a proper length, the finger 40 will be free to move sufficiently to enable the key lever 25 to disengage the latch 28 from the dog 21, thereby releasing the lever 17 and permitting operation thereof under the influence of the weight 23.

According to the present invention, the operator may, at the completion of each line,

press the key 27, whereupon the elevator will rise automatically to its upper position without further manual effort or attention on the part of the operator, the elevator being held 5 in its upper position by the usual means until the line is removed, after which it will descend to its normal lower position and there wait until the line delivery carriage returns to its line-receiving position, the elevator then being in position to again ascend 10 with another line. The manual means for raising the elevator is unnecessary when the present invention is used, although it may be retained in the machine for the convenience 15 or accommodation of an operator accustomed thereto and unaccustomed to the power elevating means.

I claim as my invention:—

1. In machines of the class described, the combination with a vertically movable elevator, and a carriage for removing matrices therefrom, of a feeler for ascertaining if all the matrices of the line are within the elevator, and power means controlled by said 25 feeler for lifting the elevator.

2. In machines of the class described, the combination with a vertically movable elevator, and a carriage for removing matrices therefrom, of a feeler for ascertaining if all 30 the matrices of the line are within the elevator, and weight-actuated means controlled by said feeler for raising the elevator.

3. In machines of the class described, the combination with a vertically movable elevator, and a carriage for removing matrices therefrom, of a feeler for ascertaining if all 35 the matrices of the line are within the elevator, and weight-actuated means set automatically by said carriage and controlled by 40 said feeler for lifting the elevator.

4. In machines of the class described, the combination with a vertically movable assembling elevator, a delivery carriage to receive matrices from the elevator when the latter is raised, a feeler for ascertaining if 45 all the matrices of the line are within the elevator, and weight-actuated means controlled by said feeler and set automatically by said carriage to overbalance and lift the 50 elevator when said carriage is in one position and rendered inactive when said carriage occupies another position.

5. In machines of the class described, the combination with a vertically movable assembling elevator, a delivery carriage to receive matrices from the elevator when the latter is raised, a feeler for ascertaining if all 55 the matrices of the line are within the elevator, and lifting means for the elevator controlled by said feeler and embodying a

shiftable weight set in position to lift the elevator when the carriage occupies one position and shiftable into an inactive position when the carriage occupies another position.

6. In machines of the class described, the combination with a vertically movable assembling elevator, a delivery carriage to receive matrices from the elevator when the latter is raised, a feeler for ascertaining if all 65 the matrices of the line are within the elevator, and lifting means for the elevator controlled by said feeler and embodying a shiftable weight set by said carriage to lift the elevator when the carriage is in position to receive a line of matrices therefrom and 70 shiftable into an inactive position by said carriage as the latter moves from its matrix-receiving position.

7. In a machine of the linotype class, in combination, the vertically movable assembling elevator, the overhead horizontally movable delivery carriage, a feeler for ascertaining if all the matrices of the line are within the elevator, and a movable weight 80 connected to both the said elevator and carriage, said weight being adapted to normally overbalance the elevator and to be moved by the carriage in order to reduce its balancing power, the lifting of the elevator by said weight being controlled by said feeler. 85

8. In machines of the class described, the combination with an assembling elevator, a delivery carriage to receive a line of matrices therefrom when the elevator is raised, means for lifting the elevator, and a feeler 95 for ascertaining if all the matrices of the line are within the elevator and controlling the raising of the elevator by said lifting means.

9. In a machine of the class described, in 100 combination with an assembling elevator, of a feeler for ascertaining if all the matrices of the line are within the elevator, and automatic means controlled by the feeler for raising the elevator. 105

10. In combination, the assembling elevator for receiving a line of matrices as they are assembled, a feeler for ascertaining if all the matrices of the line are within the elevator, means for lifting said elevator, a lock 110 to prevent the operation of said lifting mechanism, and means for controlling the lock by the feeler.

In testimony whereof I have hereunto set my hand in presence of two subscribing witnesses. 115
